UNITED STATES PATENT OFFICE.

JOHN COCKERELL, OF SOUTH YAN YEAN, VICTORIA, ASSIGNOR TO ROBERT HARPER, OF MELBOURNE, VICTORIA.

POTATO-PLOW.

SPECIFICATION forming part of Letters Patent No. 651,131, dated June 5, 1900.

Application filed March 16, 1899. Serial No. 709,347. (No model.)

To all whom it may concern:

Be it known that I, JOHN COCKERELL, blacksmith, a subject of the Queen of Great Britain and Ireland, and a resident of Plenty 5 road, South Yan Yean, in the Colony of Victoria, have invented a certain new and useful Improved Potato-Plow, of which the following is a specification.

This invention relates to an improved potato-plow or potato-digger, the main feature in which consists in the employment of a circular radially-pronged revolving sifting device arranged immediately behind a front share which is just deep and wide enough to 15 cut the earth about the row of potatoes. Said radially-pronged device is supported on a central axle, and it rotates in an oblique plane by reason of its edge or points engaging the land during the onward movement of the implement. By the radially-pronged device lying 20 obliquely it serves a double purpose: First, it separates the tubers from the earth, and, second, it delivers those which cannot pass between the prongs in a row along the off side 25 of the implement.

The invention also relates to other features of construction, which, together with the foregoing, will be fully described and explained by reference to the accompanying sheets of 30 drawings, in which—

Figure 1 is a side view, and Fig. 2 a plan, of a potato-plow constructed in accordance with my invention; Fig. 3, a front view of the share and its attached parts; Figs. 4, 5, and 35 6, detail views of the adjustable bracket-bearing and axle of the radially-pronged device; Fig. 7, a part plan of the radially-pronged device when made without a rim, and Fig. 8 a central section through boss of radially- 40 pronged device when furnished with a cone on upper face of boss to prevent earth lying thereon.

In constructing a single-furrow potato-plow embodying my improvements a beam 45 A, following the form of an ordinary single plow-beam, is employed, and said beam supports from cross-bars A' at its fore end two traveling wheels A², the vertical stems A³ of which are capable of adjustment in order to 50 determine the depth at which the share B will cut. Said share is made in the form shown,

and it is supported at its point b by the shoe-piece C, while its upper part takes the form of a plow-foot b', which is clamped to the plow-beam A. Also the share has short prongs 55 b² at its back edge, the points of which just clear and about coincide with the plane of the radially-pronged device D, which has a short axle D' at its center seated in a box-bearing E, carried by an attached arm E', which is 60 bolted to the part f of an adjustable bracket F, which is in turn secured to the sole-plate C of the plow. The radially-pronged device D is constructed of a central boss d, having arms d' projecting radially from it, said arms 65 being flattened at their outer parts and either provided with a light metal rim d², as in Figs. 1 and 2, or without it, as shown in Fig. 7. Also the central boss d may either be formed with slots d³, as shown in Figs. 1, 2, and 5, or 70 be solid, as shown in Fig. 8, and have a cone d⁴ on its upper surface secured with a screw pin or bolt d⁵. The box-bearing E has a screwed cap E², which bears on a collar d⁶, for which a recess is provided in the box-bearing 75 ing, and said collar runs, preferably, on balls e. d' is an oilway in axle D', said way being sealed by a screw d⁸.

The arm E' is secured to the bracket-piece f by bolts f' passing through curved slots 80 therein, and the part f to the bracket F by the bolt f², while part F is secured to the sole-plate C by bolts f³. By means of the adjustable bracket the height and incline of the radially-pronged device can be adjusted. The 85 back part of the sole-plate C is secured to a foot-piece G, the upper end of which is clamped to the plow-beam, while at its lower part it has a guide or center board g, pivoted at g' and capable of being secured at the desired position by a bolt g², the purpose of the center board being to cause the plow to take a straight course.

H represents delivery-prongs which may be arranged at about the position shown above 95 the radially-pronged device D to lead lumps of earth, weeds, and potatoes off its surface, said prongs being secured at H' to the arm H², descending from plow-beam.

I (shown in dotted lines) represents angularly-arranged prongs which may be required when the potatoes are small to lead those 100

which fall through the radially-pronged device to the side of furrow, and J represents arms or fingers to clean the rim of the radially-pronged device D.

5 The plow when of the single-furrow type is furnished with the usual handles at back and at front with the usual draft-gear.

When the potato-plow is at work, the share B is set to just cut under and about the row 10 of potatoes or tubers and in the onward movement of the plow lifts the cut earth onto the radially-pronged device D, whereon the earth is sifted and falls through the prongs, while the tubers are retained above and are delivered by reason of the radially-pronged device lying oblique or inclined in a row along 15 the off side of the implement.

Although this implement has been designed for use as a potato-plow, I wish it understood 20 that it may also be used for raising or digging onions or sugar-beets.

Having now described my invention, what I claim as new, and desire to secure by Letters Patent, is—

25 1. In a potato-plow, a radially-pronged rotary sifting device as D having an axle D' which works in a bearing carried by an ad-

justable bracket said sifting device being supported at an oblique angle toward the side and front of implement and with its lower 30 edge engaging the ground so that the onward movement of implement gives motion to said sifting device combined with a share having backwardly-projecting fingers which lie in the same plane of inclination and adjacent to said 35 rotary-pronged device, substantially as described.

2. In a potato-plow in combination a circular-pronged device as D, furnished with a central axle as D', and an adjustable bracket as 40 F, supporting the axle-box secured on the sole-plate of plow, substantially as described and shown.

3. In a potato-plow in combination, a circular-pronged device as D, and a series of prongs 45 as H, arranged to lie above said circular-pronged device substantially as described and shown.

In witness whereof I have hereunto set my hand in presence of two witnesses.

JOHN COCKERELL.
